CLOSURE AND FASTENER FOR THREADED CONTAINERS

Paul W. Carpenter, Fort Worth, Tex.

Application March 28, 1949, Serial No. 83,964

5 Claims. (Cl. 220—32)

1

This invention relates to closures for threaded containers, particularly containers having a screw-threaded neck, such as collapsible metal tubes, commonly employed for holding and dispensing toothpaste, shaving cream, ointments, edible pastes, and the like.

An object of the invention is to provide a closure for a threaded container that is simply and securely closed and locked in closed position, yet which is readily and quickly opened without the necessity for completely unscrewing and removing the closure.

Another object is to provide a closure of this type that is not easily lost or mislaid.

Another object is to provide, in such a closure, means whereby the closure may be securely locked for shipment and traveling purposes and may quickly be unlocked and adjusted for manual latching and unlatching in service.

Typically, the invention takes the form of a closure for a container or the like having a screw-threaded neck, the closure including an internally threaded ring adapted to be screwed on the neck of the container, a cap pivoted to the ring, the ring having a resilient portion flexible inwardly of the ring, and cooperating latch elements on the cap and on the resilient portion of the ring. In an illustrative form of the invention, the ring is threaded internally substantially entirely therethrough, the cap is secured to the ring by means of a hinged joint and the resilient sector or portion of the ring takes the form of a spring finger defined by a pair of slots extending through the ring, the spring finger being integrally rooted to the ring. The cooperating or complementary latch elements may include a radially projecting detent extending outwardly from the free end of the spring finger and a cooperating notch formed in the cap to retain the cap in closed position.

The invention will be described in greater detail and other of its objects and advantages will be in part apparent and in part pointed out in the following detailed description of an embodiment of the invention as shown in the accompanying drawing, wherein:

Fig. 1 is an elevational view of the upper portion of a collapsible metal tube showing the closure of the invention attached thereto;

Fig. 2 is a similar view showing the closure member in section with the cap in locked position;

Fig. 3 is a similar view showing the closure in section and the cap unlocked and partially open;

Fig. 4 is a side elevation of the closure taken

2 at right angles to the views of Figs. 1, 2 and 3, and showing the cap in open position;

Fig. 5 is a sectional view through the closure ring taken along the line 5—5 of Fig. 3; and

Fig. 6 is a plan view of the closure shown in the previous figures, the cap being closed.

Referring to the drawing, particularly to Figs. 1, 2 and 3 thereof, there is shown a conventional toothpaste tube 10 having a conical top portion 11 and an upstanding screw-threaded neck 12 through which the contents of the tube are dispensed. The closure of the invention includes a ring member 13 having a cap 14 pivoted thereto by the hinge 15. The cap has a depending rim 16 that forms a skirt about the upper portion of the ring member 13 when the cap is closed. Secured to the underside of the top of the cap is a sealing disc 17 of cork or similar material that engages the top of the container neck when the closure is seated to seal the container.

As best seen in Figs. 4 and 5, the ring member 13 is provided with a pair of substantially parallel slots 18 that are formed in or are cut into the ring from the top rim thereof downwardly through the material of the ring. The slots extend downwardly through one or more of the threads formed in the ring and define an upstanding finger 19 that is integrally rooted with the material of the ring. The upstanding finger 19 is typically disposed diametrically across the ring from the hinge. Preferably the ring 13 is formed from a material such as synthetic resin, metal, or the like, that has inherent resilience or springiness. To increase the flexibility of the finger 19, the slots 18 may terminate at their lower ends in a thread depression where the ring 13 has its thinnest section.

Extending radially outwardly of the ring from the top free end of finger 19 is an integral projection 20 having a downwardly and outwardly sloping upper face 21 and a downwardly and inwardly sloping lower face 22. This projection forms a detent that engages in the notch or recess 23 formed in the cap 14 when the cap is in closed position as shown in Fig. 2.

Referring to Fig. 3, it will be understood that because of the natural springiness of the material from which the ring is formed, the cap may be closed by simply moving it downwardly. The bottom of the rim 16 engages the upper cam surface 21 of the projection 20 and forces the finger 19 inwardly, in which direction it is free to move because of the partial unscrewing of the ring and the fact that the tube neck does not prevent the movement. When the cap is fully

closed, the finger springs back to engage the detent 20 in the notch 23. If the closure is left in partially unscrewed position, the pivoted cap can be snapped open and closed at will. However, when the cap is closed and the closure is screwed fully down on the container neck as shown in Fig. 2, the back of the spring finger 19 is contacted by the threaded neck of the container and is prevented from flexing inwardly. Thus, the detent 20 is maintained in the notch 23 so that the cap 14 is securely locked in closed position.

From the foregoing description, it will be evident that a number of minor variations may be made in the construction of the closure of the present invention without departing from the spirit thereof. For example, the spring finger 19 need not be formed integrally with the closure ring; instead, the finger may be attached in a notch formed in the ring. Moreover, the cooperating latch elements may be reversed, the notch being formed in the end of the spring finger and the cooperating projection or detent being formed on the cap. Although it is preferred that the cap be hinged as shown, other forms of pivoted joints may be employed with success; such joints may comprise ball and socket joints or joints from which the cap may be completely removed after partial opening of the cap has been accomplished.

It is also apparent that the principles of the invention may be applied to plug type closures as distinguished from a closure utilizing an internally threaded ring.

I claim:

1. A closure for a container or the like having a screw-threaded neck comprising a resilient ring having internal threads extending substantially entirely therethrough and being adapted to be screwed on the neck of the container, a cap pivoted to said ring, said ring having a pair of slots extending thereinto defining a spring finger integrally rooted to said ring, and cooperating latch elements on said cap and on said spring finger.

2. A closure for a container or the like having a screw-threaded neck comprising a resilient ring having internal threads extending substantially entirely therethrough and being adapted to be screwed on the neck of the container, a cap pivoted to said ring, said ring having a pair of slots extending thereinto defining a spring finger integrally rooted to said ring, a latch element projecting radially outwardly from the free end of said finger, and a notch formed in said cap and positioned to engage said latch element to retain the cap in closed position.

3. A closure for a container or the like having a screw-threaded neck comprising a resilient ring having internal threads extending from the top of said ring downwardly therein for a substantial distance, said ring being adapted to be screwed on the neck of the container with sub-

stantially complete engagement of the internal threads of the ring with the threaded portion of the neck, a cap pivoted to said ring and swingable to a closed position in which it covers the top of said ring, said ring having a pair of vertical slots opening into the top edge of said ring and extending substantially downwardly thereinto defining a spring finger integrally rooted to the ring, the internal threaded portion of said ring being formed at least in part in the internal face of said spring finger, and cooperating latch elements on said cap and on said spring finger.

4. A closure for a container or the like having a screw-threaded neck comprising a ring having internal threads extending from the top of said ring downwardly therein for a substantial distance, said ring being adapted to be screwed on the neck of the container with substantially complete engagement of the internal threads of the ring with the threaded portion of the neck, a cap pivoted to said ring and swingable to a closed position in which it covers the top of said ring, a pair of vertical slots opening into the top edge of said ring and extending substantially downwardly thereinto defining a spring finger rooted to the ring, the internal threaded portion of said ring being formed at least in part in the internal face of said spring finger, and cooperating latch elements on said cap and on said spring finger.

5. A closure for a container or the like having a screw-threaded neck comprising a ring having threads extending from the top of said ring downwardly for a substantial distance, said ring being adapted to be screwed to the neck of the container with substantially complete engagement of the threads of the ring with the threaded portion of the neck, a cap pivoted to said ring and swingable to a closed position in which it covers the opening of said ring, said ring having a pair of vertical slots opening into the top edge of said ring and extending substantially downwardly thereinto defining a spring finger rooted to the ring, the threaded portion of said ring being formed at least in part in a face of said spring finger, and cooperating latch elements on said cap and on said spring finger.
